DEVICE FOR MOUNTING COIL UNITS ON APERTURED SUPPORTS

Filed April 7, 1950

INVENTOR:
CLARENCE WILLIAMS HEATH,

By Philip E. Parker

ATTORNEY.

UNITED STATES PATENT OFFICE

2,677,972

DEVICE FOR MOUNTING COIL UNITS ON
APERTURED SUPPORTS

Clarence Willans Heath, Bleasby, England, assignor to United-Carr Fastener Corporation, Cambridge, Mass., a corporation of Massachusetts

Application April 7, 1950, Serial No. 154,641

3 Claims. (Cl. 74—424.8)

1

This invention relates to a sheet metal device for mounting a coil former on an apertured support and more particularly to mounting devices of the kind including nut means adapted to make screwed engagement with a threaded rod extending from the coil former and resilient arms between which the coil former is adapted to be positioned and secured.

It is an object of the invention to provide an improved mounting device of the above-mentioned kind.

According to the present invention a sheet metal device of the kind referred to for mounting a coil former on an apertured support comprises an apertured base having resilient arms extending from one face thereof and formed with inwardly directed lugs for engaging a coil former inserted between them, and integral resilient legs extending from the opposite side of the base and formed with inturned free ends provided with nut means for engaging a screw-threaded rod of the coil former, the base of the device having a length greater than the width of the aperture in the support whereby when it is assembled with the support portions of the base at the inner ends of the legs form shoulders adapted to abut the adjacent face of the support.

To enable the invention to be fully understood it will now be described with reference to the accompanying drawing, in which:

Fig. 1 is an elevational view of a coil former mounted on a support by means of a mounting device according to one embodiment of the invention;

Fig. 2 is an elevational view similar to Fig. 1 but taken at an angle of 90° thereto;

Fig. 3 is a side view of the mounting device;

Fig. 4 is an end view thereof, and

Fig. 5 is a plan view.

As shown in the accompanying drawing 1 is a support such as the panel of a wireless set, and 2 is an oblong shaped aperture formed therein. The permeability tuning unit to be mounted on the panel comprises a cylindrical hollow former or casing 3 in which is reciprocably mounted a screw-threaded rod 4 carrying an iron dust core. The unit is mounted on the panel by a sheet metal device comprising a base 5 having an aperture 6 and a pair of resilient legs 7 formed integrally therefrom and bent to extend from side edge portions of one surface of the base. The free ends of the legs 7 are bent to extend inwardly in spaced aligned relation with the base aperture 6 and are formed with arcuate recesses serving as nut means 8 for engaging the threads of the rod 4. The base

2

is also formed with a pair of integral resilient arms 9 extending from side edge portions of the base between the legs and from the opposite face of the base 5. The arms 9 are longer than the legs 7 and extend through the aperture 2 in the support 1 and their free ends are inturned to provide lugs 10 which are entered into apertures or recesses 11 in the wall of the former or casing 3. The arms 9 are sufficiently resilient to permit them to be forced apart to permit the insertion of the former 3 between them and allow the lugs resiliently to engage in the aperture 11.

To assemble the parts, the arms 9 are inserted through the aperture 2 until the base abuts the adjacent face of the support. As the aperture 2 is of oblong shape, the arms 9 extend lengthwise of the aperture and the legs 7 extend transversely thereof whereby the portion of the base connected with the inner ends of the legs 7 provides portions 12 extending across the width of the aperture 2 and which abut the support and prevent the mounting device being drawn axially through the aperture 2. The former 3 is inserted by forcing the arms 9 apart and inserting the former between them. The former is then moved axially towards the support 1 to enter the rod through the aperture 2 and aperture 6 in the base of the device and into screwed engagement with the nut means 8. When the former is in fully assembled position its base spans the width of the aperture 2 and rests on the adjacent portions of the support 1, and is locked by the lugs 10 of the arms 9 engaging in the aperture 11. The unit is accordingly held against axial movement by the base of the former and the shoulders 12 engaging opposite faces of the support 1, and it is adjusted as required by screwing the rod 4 upwardly or downwardly relative to the nut means 8.

It will be noted that the base 5 is curved, having a concave face (Fig. 3) directed towards the free ends of the former engaging arms. Accordingly when the arms are forced apart to receive the former 3, as shown in Fig. 1, the curved portion of the base is flattened and the base in tending to return to its original concave shape tends to urge the arms inwardly more securely to engage with the apertures 11.

Instead of the arms 9 engaging in slots in the former 3, they may be provided with sharp points adapted to dig into the wall of the former 3.

What I claim is:

1. A sheet metal device for mounting a coil former on an apertured support comprising: a plate-like base having a centrally disposed aperture, a pair of resilient arms extending integrally

over one face thereof from opposite end edges, and a pair of resilient legs extending integrally over the opposite face from opposite edges intermediate said arms, said arms being substantially narrower in width than said base and formed with inwardly directed lugs for engaging a coil former inserted between them, said legs being formed with inturned free ends provided with opposed concave edges disposed in spaced alignment to the aperture of the base for engaging the threads of a screw-threaded rod of a coil former, said arms being constructed and arranged for insertion into an elongated aperture in a support and for securing a coil former on one face of such a support while said base engages the other face of the support on opposite sides of the aperture therein, the side edges of said arms defining imaginary substantially parallel planes intersecting said base to define laterally extending portions thereof for engaging portions of such other face of the support adjacent the aperture through which said arms may extend for engaging a coil former and securing it against such one face thereof.

2. A sheet metal device in accordance with claim 1 wherein the base has a concave curved cross-section along imaginary planes substantially parallel to the imaginary planes defined by the side edges of the arms, whereby, when a coil former is assembled on a support by the device, the curved base is slightly flattened and thereby exerts a spring force tending to urge the arms into engagement with the coil former.

3. In an installation including a support having

an elongated aperture, a coil former mounted on said support with its base spanning the support aperture and resting on one face of the support, and a screw-threaded rod projecting from the coil former and extending through the support aperture, a sheet metal device for mounting the coil former on the support comprising: a plate-like base having a centrally disposed aperture, a pair of resilient arms extending over one face thereof integrally opposite end edges, and a pair of resilient legs extending over the opposite face thereof integrally from opposite edges intermediate said arms, said base spanning said support aperture and engaging the face thereof opposite to that engaged by the coil former base, said arms extending through said support aperture and having inwardly directed lugs detachably engaging said coil former securing it in tensioned engagement to the support, said legs being formed at their outer free end with opposed concave edges disposed in spaced relation to the base in screw-threaded engagement with the screw-threaded rod.
